CIRCUITS FOR CONTROLLING ELECTRIC LOCKS ON RAILWAY TRACK SWITCHES

Charles W. Failor, Forest Hills, Pa., assignor to
The Union Switch & Signal Company, Swiss-
vale, Pa., a corporation of Pennsylvania

Application February 14, 1948, Serial No. 8,406

5 Claims. (Cl. 246—160)

1

My invention relates to railway traffic controlling apparatus, and more particularly to improved apparatus for controlling electric switch locks for safeguarding the operation of outlying hand throw track switches.

An outlying track switch of the type contemplated is to be understood to be one leading to an industrial siding or the like and intended primarily for operation by the crew of a train doing local switching, after obtaining permission by telephone or otherwise, from the dispatcher or central office operator. Such switches are usually at a distance from any existing interlocking plant and are at locations having no relation to the proper location of the block signals for protecting main line train movements. These switches must be free to be operated at times when there is a train at the switch so the usual methods of safeguarding train movements over track switches located within interlocking limits are not applicable.

One object of my invention is to provide improved switch lock control means incorporating means for insuring that the signal at the entrance to the block section including the switch will be cleared only when the switch is locked in its normal position, and for controlling the signal to stop in order to allow the switch to be unlocked in response to operation of the associated time element device.

Another object of my invention is to provide an improved system of the type described which is arranged so that a switch may be unlocked without delay to permit a train on a siding to enter the main track if the main track within a predetermined distance of the switch is not occupied.

A further object of my invention is to provide an improved system of the type described which is arranged so that when the main track within a predetermined distance of a switch is occupied, the switch can be unlocked to permit a train on a siding to enter the main track only after the expiration of a time interval long enough to allow the train on the main track to stop before reaching the switch, or if unable to stop, to overrun the switch and thus prevent movement of the switch in front of the train.

Another object of the invention is to provide an improved switch lock control system which is arranged so that the lock is controlled entirely by one of the train crew at the switch.

A further object of the invention is to provide improved means of the type described which is adapted for use where there are a plurality of switches within a single track section.

Another object of the invention is to provide improved means of the type described which is arranged so that after a switch has been unlocked it will remain unlocked until it is certain that it is intended that the switch is to be locked.

2

A further object of the invention is to provide improved means of the type described which is arranged so that after a switch has been unlocked it will not be inadvertently locked before a train has completed its movements over the switch.

Another object of the invention is to provide improved switch lock control means which reduces to a minimum the number of line wires which must be provided between the switch and the first signal in the rear of the switch.

Other objects of the invention and features of novelty will be apparent from the following description taken in connection with the accompanying drawing.

In the drawing the single figure is a diagram showing a stretch of railway track including a track section in which there are two track switches equipped with locks governed by means provided by this invention.

In practicing my invention, I provide a line circuit which extends from the entrance end of a track section to the switch farthest from the entrance end of the section, and I provide means at the entrance end of the section for at times supplying energy to this line circuit. In addition, I provide means at each switch for releasing the lock for the switch when energy is received over this line circuit. When a signal control relay governed by traffic conditions in the stretch is picked up energy is supplied to this line circuit only when an approach relay is picked up to show that the track stretch leading to the section is unoccupied for a predetermined distance. Under these conditions, therefore, the switch may be unlocked without delay to permit a train on the siding to enter the main track. When the signal control relay is released energy is supplied to a time element relay and when it picks up energy is supplied to the line circuit.

Each switch lock includes means rendered effective during a preliminary part of the operation of unlocking of the switch for shunting the track circuit of the track section including the switch to thereby release the signal control relay and cause energy to be supplied to the time element relay. Accordingly, when the approach relay is released, and it is desired to reverse the switch to permit a train on the siding to enter the main track, the switch may be unlocked after an appropriate time interval, while this time interval is automatically initiated when an attempt is made to unlock the switch.

When the section is occupied this means also operates to permit the switch lock to be released after a time interval so a train on the main track may enter a siding.

Each switch lock includes means effective after the supply of energy to the lock winding has been established to maintain this supply of energy until it is certain that it is intended that the switch is to be locked even though the supply

of energy to the line circuit is cut off before the switch is to be locked.

Each switch may also be provided with a short releasing track circuit together with means effective on release of the track relay of this track circuit for energizing the associated switch lock to thereby permit immediate release of a lock so that a switch may be operated to enable a train on the main track to enter a siding.

Referring to the drawing there is shown 10 therein a stretch of railway track through which traffic normally moves in the direction indicated by the arrow, that is, from left to right. The track rails 1 and 2 are divided by insulated joints 3 into the customary track sections for signaling purposes. One complete track section together with portions of the adjoining track sections is shown. The track section which is shown in the drawing is divided by insulated joints 3 into three subsections which are designated 5CT, 5BT and 5AT. These subsections are separated by short releasing track sections AWT and BWT each of which is provided with a track circuit including a track relay. The releasing sections AWT and BWT are located immediately in advance of the track switches AW and BW which lead to side tracks.

The track rails of the subsections on opposite sides of each short releasing track section are connected together by wires governed by contacts of the track relay of the releasing section so that the three subsections 5CT, 5BT and 5AT together form one track circuit. This track circuit includes a code following track relay 5TR which is connected across the section rails at the entrance end of the section and is operated by energy supplied over the section rails from the track battery 5TB at the exit end of the section. The supply of energy from the battery 5TB to the section rails is governed by a contact of the transmitter relay 5CP, and this relay may be operated by means well known in the signaling field so as to at times cause energy of 75 code frequency and to at other times cause energy of 180 code frequency to be supplied to the track rails depending on traffic conditions in advance.

The track relay 5TR governs the supply of energy to the slow release relays 5FP and 5H, and also governs the supply of energy to the primary winding of the decoding transformer 5DT from which energy is at times supplied through a resonant rectifier unit 180DU to the relay 5D. The relays 5H and 5D cooperate to control the supply of energy to the lamps of the signal 5S which governs entrance of traffic into the section.

An approach relay 6AP is associated with relay 5H and is governed by traffic conditions in section 6T so as to be picked up only when section 6T is unoccupied. The relay 6AP may also be controlled by traffic conditions in the rear of section 6T. The means for controlling relay 6AP is not a part of this invention and this relay may be governed in any suitable manner.

A time element relay 5TE is located at the entrance end of the section and has a winding to which energy is supplied when the relays 5FP and 5H are released. The relay 5TE has normally closed checking contacts 10 and 11 which are opened as soon as energy is supplied to the relay winding, and has normally open contacts 12 and 14 which become closed only after energy has been supplied to the relay wind-

ing for a substantial time interval, such as six minutes.

5 A line circuit consisting of line wires 16 and 17 extends from the entrance end of the section to the switch BW, and, as hereinafter explained, energy is at times supplied to this line circuit over contacts of the relays at the entrance end of the section.

Each of the track switches AW and BW is provided with an operating mechanism comprising a hand throw switch stand, which may, for example, be of the type shown in Letters Patent of the United States No. 2,184,870, issued to Herbert L. Bone and Kenneth J. J. McGowan, on December 26, 1939, for Railway Switch Operating Mechanisms. The operation of each switch is governed electrically by an electric switch lock controlled by a lock magnet AWL or BWL. The electric lock may be applied directly to the lock rod of the switch in a well-known manner, but preferably it is applied to the operating lever of the switch stand.

The electric switch locks may be of the type disclosed in Letters Patent of the United States No. 1,126,834, issued to Walter P. Neubert and William E. Smith, on February 2, 1915 for Electric Switch Locks. For an understanding of the details of operation of the locking mechanism reference may be made to this patent, but for 25 an understanding of this invention it is believed that it will suffice to point out that the operating lever of each switch stand is normally locked mechanically in a position to maintain the associated track switch locked normal, by means of 30 a padlock. More particularly, a lever latch attached to a segment 25 is held in its locking position by the bail of a padlock 50, as indicated diagrammatically in the accompanying drawing, and as shown in detail in Fig. 1 of the Neubert 35 et al. patent. To unlock the switch, the padlock must first be removed by one of the train crew to permit the segment 25 to be moved a short distance to a position to engage the locking dog 27 and close the contacts 46a-47a, 46b-47b, 40 and 46c-47c. Then if traffic conditions are such that it is proper to unlock a switch, the winding of the associated lock magnet will become energized to lift the locking dog 27, permitting the 45 segment 25 to be moved to its full reverse position in which the associated switch operating lever is free to be operated. The movement of 50 a switch lever toward its reverse position projects one end of a rod 39, arranged as shown in Figs. 1, 5, and 6 of the Neubert and Smith 55 patent, into the path of the lever latch with the result that the segment 25 is held reversed and cannot be restored to its normal position as long as the switch operating lever is out of its 60 normal position.

65 It is also to be understood that each switch stand is equipped with the usual switch circuit controller and point detector having a movable contact 82 which is open only when the switch points and the operating lever for the switch are both in their normal positions.

70 Each switch has associated therewith a control relay WAR which governs the supply of energy to the winding of the associated lock magnet. Each switch control relay is provided with a pick-up winding to which energy is supplied from the line wires 16 and 17. Each switch control relay is also provided with a second or holding winding to which energy is supplied from a suitable 75 local source of direct current, such as a storage

battery, not shown, the terminals of which are designated B and C in the drawing.

The equipment is shown in the condition which it assumes when the track stretch is vacant and the switches AW and BW are locked normal. As the switches are normal the contacts 32 are open and do not shunt the track rails, and as the switches are locked the contacts 46a-47a of the switch locks are open and do not shunt the track rails, while the other contacts of the switch locks are open and interrupt the circuits for supplying energy to the switch lock windings. Accordingly, the locking dogs 27 are released and prevent movement of the segments 25 to unlock the switch operating levers.

As the contacts of the switch circuit controllers and of the switch locks are open, coded energy supplied from battery 5TB as a result of operation of the relay 5CP feeds over the section rails and over the wires by-passing the short releasing track sections AWT and BWT to the winding of the track relay 5TR. As a result of the supply of coded energy to the winding of relay 5TR the relay contact picks up and releases. During the picked-up periods of contact 20 of relay 5TR energy is supplied to relay 5FP and its contacts are picked up with the result that during the released periods of the relay 5TR energy is supplied to relay 5H over the circuit which includes back contact 20 of relay 5TR, back contacts 10 and 11 of relay 5TE in series, and front contact 21 of relay 5FP. The relays 5FP and 5H are snubbed by rectifiers so that they are slow enough in releasing to remain picked up as long as the relay 5TR is responding to coded energy.

In addition, as a result of code following operation of the track relay 5TR the two portions of the primary winding of the decoding transformer 5DT are alternately energized and energy is induced in the transformer secondary winding. When the relay 5TR is operated by coded energy of 180 code frequency, as is the case when the track stretch is vacant, the energy induced in the secondary winding of the transformer 5DT is of such frequency that sufficient energy is supplied through the resonant rectifier unit 188DU to pick up the contacts of relay 5D. As the relays 5H and 5D are picked up an obvious circuit is established for supplying energy to the green or clear lamp of the signal 5S.

The relay 5H may be employed in the manner well known in the art to govern the supply of coded energy to the rails of section 6T, and thus control approaching traffic in accordance with traffic conditions in the section which includes the track switches.

As the relays 5FP and 5H are picked up the circuit of the time element relay 5TE is open at back contact 22 of relay 5H and at back contact 23 of relay 5FP. Accordingly, the contacts of relay 5TE are released at this time.

As the track stretch is assumed to be vacant the approach relay 6AP is picked up with the result that terminal B of the local source is connected over front contact 22 of relay 5H and front contact 32 of relay 6AP to line wire 16, and terminal C of the local source is connected over front contact 31 of relay 5FP and front contact 32 of relay 6AP to line wire 17. Accordingly, energy is supplied to the line wires 16 and 17 so that energy is supplied from these line wires to the pick-up windings of the relays AWAR and BWAR and their contacts are picked up, but their contacts do not establish the circuits for supply-

ing energy to the windings of the switch locks and they remain deenergized.

With the equipment in the condition illustrated in the drawing, a switch lock may be released without delay to permit a switch to be reversed to enable a train on a side track to enter the main track. If, for example, a trainman wishes to reverse switch AW to permit a train on the siding to enter the main track, he will remove the padlock from the lock AWL. When the bail of the padlock 50 is removed the segment 25 is permitted to move far enough to close the contacts 46 and 47 of the switch lock. When contacts 46b-47b and 46c-47c close, a circuit including front contacts of relay AWAR is established for supplying energy from a local source to the lower or holding winding of relay AWAR and to the winding of the lock AWL. The various parts of the equipment are arranged so that the energy supplied from the local source to the lower or holding winding of the relay AWAR is of the same polarity as that supplied from the line circuit to the upper or pick-up winding of the relay. Accordingly, the relay contacts are maintained picked up by energy supplied to the relay holding winding after the supply of energy to the relay pick-up winding is cut off. As long as the contacts of relay AWAR remain picked up energy is supplied to the relay holding winding and also to the winding of the lock AWL. The energy supplied to the winding of the lock AWL causes the locking dog 27 to be lifted out of the path of the segment 25 and permits the segment to move to its full reverse position in which the associated switch lever is free to be operated.

In addition, when the contacts 46 and 47 of the switch lock AWL close, contacts 46a-47a establish a connection between the track rails which shunts the track relay 5TR. Accordingly, the track relay 5TR remains released and relays 5FP, 5H, and 5D become released. As a result of release of relays 5FP and 5H the supply of energy to the line wires 16 and 17 is interrupted, but as explained above, energy is supplied to the holding winding of the relay AWAR before the supply of energy over the line wires 16 and 17 to the relay pick-up winding is cut off so the relay AWAR remains picked up and maintains the supply of energy to the winding of the lock AWL. On interruption of the supply of energy to the line wires 16 and 17 the supply of energy to the pick-up winding of relay BWAR is cut off and the contacts of this relay release and prevent energization of the associated lock BWL.

On release of relay 5H the circuit of the red or stop lamp R of the signal 5S is established, and on release of relays 5FP and 5H the circuit for supplying energy to the winding of the time element relay 5TE is established and its contacts become picked up. The back contacts 10 and 11 open promptly on the supply of energy to the relay winding, and when open interrupt the circuit of relay 5H to hold the signal 5S at stop. The contacts 12 and 14 of relay 5TE become closed only after energy has been supplied to the relay winding for a substantial time interval, such as six minutes. When contacts 12 and 14 of relay 5TE become closed connections are established for supplying energy to the line wires 16 and 17 as long as relays 5FP and 5H are released. When energy is supplied to wires 16 and 17 energy is supplied therefrom to the pick-up windings of the relays AWAR and BWAR. As the contacts of relay AWAR are picked up the supply of energy to the relay pick-up winding

has no effect, but the energy supplied to the pick-up winding of relay BWAR picks up the relay contacts to permit energy to be supplied to the associated lock if it is desired to move the switch BW.

As soon as the operating lever of the switch AW is moved away from its normal position, the rod 39 moves into the path of the segment 25 and holds it reversed to thereby hold the contacts 46 and 47 closed. In addition, when the operating lever for the switch AW is moved the contact 82 governed thereby establishes a connection between the track rails 1 and 2 to thereby shunt the track relay 5TR and prevent its operation. This insures that the signal 5S is held at stop as long as the switch AW is not in its normal position.

After the switch AW is reversed the train on the siding may enter the main track. As soon as the train enters section AWT the relay ATR releases and its contacts interrupt connection between the portions of the track rails on opposite sides of the section AWT and shunt the portion of the rails at the left of this section. This insures that relay 5TR will remain released and that signal 5S is held at stop.

When the operating lever for the switch AW is restored to its normal position, the contact 82 associated with this switch is opened.

When the operating lever of the switch AW is restored to its normal position, the contacts 46-47 of the associated switch lock are unaffected and remain closed. Hence the supply of energy to the holding winding of relay AWAR, and to the winding of the lock AWL, is maintained and the lock AWL remains released to permit operation of the switch if this is desired. The arrangement of the apparatus is such, therefore, that once an unlock of a switch is secured, the switch will not be inadvertently locked when the operating lever for the switch is restored to normal.

When the train completes its movements over the switch AW, one of the crew replaces the padlock 50 on the lock AWL. When the padlock is replaced on the lock AWL the segment 25 of the lock is restored to its normal position and the contacts 46-47 of the lock are opened. When contacts 46a-47a are opened the connection between the track rails is interrupted, but at this time the presence of the train in the track stretch prevents the track relay 5TR from operating and thus holds signal 5S at stop.

In addition, when contacts 46b-47b and 46c-47c are opened the circuit for supplying energy to the holding winding of relay AWAR, and to the winding of the lock AWL, is interrupted. Accordingly, the contacts of relay AWAR release and the locking dog 27 of the lock AWL released.

When the train under consideration vacates the track section coded energy supplied from battery 5TB feeds over the section rails and operates the track relay 5TR to pick up relay 5FP so that its contact 23 interrupts the circuit of the winding of relay 5TE with the result that its contacts release. When the contacts of relay 5TE release, contacts 10 and 11 in the circuit of relay 5H are closed and on continued code following operation of relay 5TR energy is supplied to relay 5H and its contacts pick up to additionally interrupt the circuit of relay 5TE. In addition, when the relay 5H picks up one of its contacts interrupts the circuit of the red lamp R of signal 5S and establishes the circuit gov-

erned by a contact of relay 5D for supplying energy to the yellow or the green lamp of signal 5S.

As soon as relay 5FP picks up its contact 5 31 interrupts the circuit governed by front contacts of relay 5TE for supplying energy to the line wires 16 and 17. This circuit is additionally interrupted on release of contacts 12 and 14 of relay 5TE, and on picking up of contact 22 of relay 5H. When relays 5FP and 5H are picked up energy may be supplied over their front contacts and over front contacts of relay 6AP to the line wires 16 and 17, and thus to the pick-up windings of the relays AWAR and BWAR so the contacts of these relays pick up. When this occurs, the equipment is again in substantially the condition in which it is illustrated in the drawing.

The equipment operates so that if, at the time 20 an attempt is made to unlock a switch to permit a train on a siding to enter the main track, the portion of the track stretch within a predetermined distance in the rear of the switch is occupied so that relay 6AP or relay 5H is released, 25 the lock may be released only after the expiration of the time interval determined by relay 5TE. This time interval is long enough to enable an approaching train to stop before reaching the switch, or to overrun the switch and thus prevent opening of the switch in front of the train.

When relay 6AP is released its contacts 30 and 32 interrupt the connections including front contacts of relays 5FP and 5H and over which energy is supplied to line wires 16 and 17. Similarly, 35 when relay 5H is released the connections for supplying energy to the line wires 16 and 17 are interrupted. Accordingly, the relays AWAR and BWAR are released and their contacts interrupt the circuits for supplying energy to the relay holding windings and to the windings of the switch locks.

If an attempt is now made to unlock the lock AWL, and the padlock is removed from this lock, the segment 25 will move to a position to cause 45 the associated contacts 46 and 47 to close. When contacts 46b-47b and 46c-47c close, energy is not supplied to the holding winding of relay AWAR and to the winding of the lock AWL since the circuit of these windings is open at the contacts of relay AWAR. When contacts 46a-47a close, a connection is established between the track rails so the track relay 5TR ceases to operate and relays 5FP and 5H release, if they are not already released, to establish the circuit of 50 the winding of relay 5TE and to also cause signal 5S to display its stop indication. As soon as energy is supplied to relay 5TE its contacts 10 and 11 pick up to interrupt the circuit of relay 5H and hold the signal 5S at stop. The contacts 55 12 and 14 of relay 5TE do not become closed until energy has been supplied to the winding of relay 5TE for a substantial time interval, and until the contacts 12 and 14 become closed, the supply of energy to the line wires 16 and 17 is interrupted. 60 As long as the supply of energy to the line wires 16 and 17 is interrupted the relay AWAR is released and prevents the supply of energy to the winding of the lock AWL.

When the contacts 12 and 14 of relay 5TE become 65 picked up energy is supplied to the line wires 16 and 17 and, therefore, is supplied from these wires to the pick-up winding of relay AWAR and its contacts pick up to establish the circuit for supplying energy to the relay holding winding 70 and to the winding of the lock AWL. The

switch AW may now be moved, and the operation of the equipment at this time is the same as previously described in detail and need not be repeated.

This equipment is also arranged so that a switch may be unlocked without delay to permit a train on the main track to enter a siding.

When a train on the main track advances into section 5CT the track relay 5TR releases and remains released so that relays 5FP and 5H become released and cause signal 5S to display its stop indication.

When the train advances into section AWT the relay ATR releases and its back contacts 33 and 34 in the connections for supplying energy from the local source to the lower winding of relay AWAR, and to the winding of the lock AWL, are closed. The circuits for supplying energy to the lower winding of relay AWAR and to the winding of the lock AWL are complete as soon as the padlock is removed from the switch lock so that contacts 46b—47b and 46c—47c become closed. Hence the lock is released promptly and the switch may be reversed without delay to permit the train to enter the siding.

When relay AWAR picks up its contacts establish connections to maintain the supply of energy to the relay holding winding, and to the winding of the lock AWL, in the event that section AWT is vacated and relay ATR picks up.

The operation of the equipment after movement of the switch, and after the train vacates the main track and the switch is restored to normal, is similar to that described in detail above and need not be repeated.

As explained above, when a train on the main track enters section 5CT, the relays 5FP and 5H release and establish the circuit for supplying energy to the winding of the relay 5TE. If the train occupies the section long enough, the contacts 12 and 14 of relay 5TE will become picked up and complete the connections for supplying energy to the line wires 16 and 17 with the result that energy is supplied to the pick-up windings of relays AWAR and BWAR and their contacts are picked up to cause energy to be supplied to the winding of a lock as soon as an attempt is made to unlock a switch. It is proper for a switch to be unlocked under these conditions as the train in the section will have stopped or will be moving at such a low speed that the switch will not be a hazard. The arrangement just described enables a switch lock to be released in the event the equipment for a short releasing section is not functioning properly, or if these sections are not provided.

The equipment associated with switch BW operates in substantially the same manner as the equipment associated with switch AW and a detailed explanation of its operation is unnecessary.

Although I have herein shown and described only one form of switch lock control means embodying my invention, it is understood that various changes and modifications may be made therein within the scope of the appended claims without departing from the spirit and scope of my invention.

Having thus described my invention, what I claim is:

1. In combination with a section of railway track including a hand throw switch, means comprising a mechanical lock and an electric lock for preventing the hand operation of said switch, said section being provided with a track circuit including track relay means which is energized

in response to energy supplied over the section rails, a signal governing entrance of traffic into said section, said signal being governed by said track relay means so as to display a permissive or a stop indication according as said track relay means is energized or deenergized, an approach zone including at least one track section located in approach to said signal, an approach relay governed by traffic conditions in said approach zone so as to be energized only when said approach zone is unoccupied, a time element device having normally open contacts which become closed only after energy has been supplied to the winding of said device for a substantial time interval, means effective when said track relay means is deenergized for supplying energy to said time element device, a line relay associated with said switch, means for supplying energy to said line relay when said track relay means is energized provided said approach relay is energized, means for also supplying energy to said line relay when said track relay means is deenergized provided the contacts of said time element device are closed, means at said switch effective when said mechanical lock is released for preventing the supply of energy over the rails of said section to said track relay means, and means at said switch effective when said mechanical lock is released provided said line relay is energized for supplying energy to said line relay and for also supplying energy to said electric lock to unlock said switch.

2. In combination with a block section of railway track including a hand throw switch, means comprising a mechanical lock and an electric lock for preventing the hand operation of said switch, said section being provided with a track circuit including track relay means at one end which is energized in response to energy supplied over the section rails, a signal at said one end governing entrance of traffic into said section, said signal being governed by said track relay means so as to display a permissive or a stop indication according as said track relay means is energized or deenergized, an approach zone including at least one track section located in approach to said signal, an approach relay governed by traffic conditions in said approach zone so as to be energized only when said approach zone is unoccupied, a time element device having normally open contacts which become closed only after energy has been supplied to the winding of said device for a substantial time interval, means effective when said track relay means is deenergized for supplying energy to said time element device, a line circuit extending from said signal to said switch, means for supplying energy to said line circuit when said track relay means is energized provided said approach relay is energized, means for also supplying energy to said line circuit when the normally open contacts of said time element device are closed, means at said switch effective when said mechanical lock is released for cutting off the supply of energy over the rails of said section to said track relay means, and means at said switch effective when said mechanical lock is released for supplying energy to said electric lock to unlock said switch provided energy is received at said switch over said line circuit.

3. In combination, a section of railway track through which traffic normally moves in a selected direction, said track section including a hand throw switch at an intermediate point in said section, said track section being divided into a plurality of portions including a detector portion adjacent said switch, said detector portion

being provided with a track circuit including a track relay, said track section being provided with a track circuit including track relay means at the entrance end of said section energized in response to energy which is supplied over the section rails only when the entire section is unoccupied, a signal governing entrance of traffic into said section, said signal being governed by said track relay means so as to display a permissive or a stop indication according as said track relay means is energized or is deenergized, an approach zone including at least one track section in approach to said signal, an approach relay governed by traffic conditions in said approach zone so as to be energized only when said approach zone is unoccupied, a time element device having normally open contacts which become closed only after energy has been supplied to the winding of said device for a substantial time interval, means effective when said track relay means is deenergized for supplying energy to said time element device, a line relay associated with said switch, means for supplying energy to said line relay when said track relay means is energized provided said approach relay is energized, means for also supplying energy to said line relay when the contacts of said time element device are closed, an electric lock normally effective to lock said switch in its normal position as required for traffic movements through said section, a manually operable mechanical lock for preventing the operation of said electric lock, means at said switch effective when said mechanical lock is released for cutting off the supply of energy over the rails of said section to said track relay means, and means at said switch effective when said mechanical lock is released for supplying energy to said electric lock to unlock said switch.

4. In combination, a section of railway track through which traffic normally moves in a selected direction, said track section including a hand throw switch at an intermediate point in said section, said track section being divided into a plurality of portions including a detector portion adjacent said switch, said detector portion being provided with a track circuit including a track relay, said track section being provided with a track circuit including track relay means at the entrance end of said section energized in response to energy which is supplied over the section rails only when the entire section is unoccupied, a signal governing entrance of traffic into said section, said signal being governed by said track relay means so as to display a permissive or a stop indication according as said track relay means is energized or is deenergized, an approach zone including at least one track section in approach to said signal, an approach relay governed by traffic conditions in said approach zone so as to be energized only when said approach zone is unoccupied, a time element device having normally open contacts which become closed only after energy has been supplied to the winding of said device for a substantial time interval, means effective when said track relay means is deenergized for supplying energy to said time element device, a line relay associated with said switch, means for supplying energy to said line relay when said track relay means is energized provided said approach relay is energized, means for also supplying energy to said line relay when the contacts of said time element device are closed, means at said switch effective when said mechanical lock is released for also supplying energy to said line relay when said mechanical lock is released, and means at said switch effective when said mechanical lock is released for supplying energy to said electric lock to unlock said switch.

released for cutting off the supply of energy over the rails of said section to said track relay means, an electric lock normally effective to lock said switch in its normal position as required for traffic movements through said section, a manually operable mechanical lock for preventing the operation of said electric lock, means at said switch effective when said mechanical lock is released provided said line relay is energized for supplying energy to a winding of said line relay to maintain said line relay energized, and means at said switch effective when said mechanical lock is released provided said line relay is energized or the track relay of said detector portion is released for supplying energy to said electric lock to unlock said switch.

5. In combination, a section of railway track through which traffic normally moves in a selected direction, said track section including a hand throw switch at an intermediate point in said section, said track section being divided into a plurality of portions including a detector portion adjacent said switch, said detector portion being provided with a track circuit including a track relay, said track section being provided with a track circuit including a track relay means at the entrance end of said section energized in response to energy which is supplied over the section rails only when the entire section is unoccupied, a signal governing entrance of traffic into said section, said signal being governed by said track relay means so as to display a permissive or a stop indication according as said track relay means is energized or is deenergized, an approach zone including at least one track section in approach to said signal, an approach relay governed by traffic conditions in said approach zone so as to be energized only when said approach zone is unoccupied, a time element device having normally open contacts which become closed only after energy has been supplied to the winding of said device for a substantial time interval, means effective when said track relay means is deenergized for supplying energy to said time element device, a line circuit extending from said signal to said switch, means effective when said track relay means is energized provided said approach relay is energized for supplying energy to said line circuit, means effective when the contacts of said time element device are closed for also supplying energy to said line circuit, an electric lock normally effective to lock said switch in its normal position as required for traffic movements through said section, a manually operable mechanical lock for preventing the operation of said electric lock, means at said switch effective when said mechanical lock is released for supplying energy to said electric lock to unlock said switch provided energy is received at said switch over said line circuit, and means at said switch effective when said mechanical lock is released for also supplying energy to said electric lock to unlock said switch provided the track relay of said detector portion is released.

CHARLES W. FAILOR.
